UNITED STATES PATENT OFFICE.

ELZIE HARNESS, OF BLOOMINGTON, ILLINOIS.

GOLF-CLUB HEAD.

Application filed February 14, 1923. Serial No. 618,961.

To all whom it may concern:

Be it known that I, ELZIE HARNESS, a citizen of the United States, residing at Bloomington, in the county of McLean and

5 State of Illinois, have invented a new and useful Golf-Club Head, of which the following is a specification.

This invention relates to game apparatus and more particularly to golf clubs.

10 The object of the invention is to provide a golf club head which is practically indestructible combining the qualities of lightness with strength and durability.

With the foregoing and other objects in view which will appear as the description proceeds, the invention resides in the combination and arrangement of parts and in the details of construction hereinafter described and claimed, it being understood 20 that changes in the precise embodiment of the invention herein disclosed may be made within the scope of what is claimed without departing from the spirit of the invention.

In the accompanying drawings:

25 Figure 1 represents a top plan view of a golf club head constructed in accordance with this invention.

Fig. 2 is a side elevation thereof.

Fig. 3 is a bottom plan view thereof.

30 Fig. 4 is a longitudinal section taken on the line 4—4 of Fig. 1, and

Fig. 5 is a transverse section taken on the line 5—5 of Fig. 1.

The head constituting this invention comprises a metal casing 1 preferably constructed of aluminum and shaped to conform to the shape of an ordinary golf head having a tubular extension 2 at its rear end to receive the handle or stick, not shown.

40 This casing 1 is flattened at one side and provided with a removable side 3 secured in position by screws 4 which enter the filler or insert 5 which is constructed of any suitable hard wood. These screws operate

45 not only to hold the side 3 in operative position, but to retain the filler or insert in the casing.

The insert 5 is further secured in the casing 1 by means of screws 6 which enter through the bottom of the casing, having 50 their heads counter-sunk as is shown clearly in Fig. 5.

The tubular extension 2 has the bore 7 thereof arranged at an oblique angle to receive the golf club stick or handle, not 55 shown, which is secured therein in any suitable or desired manner. A golf club head constructed as herein shown and described is practically indestructible, since the wooden filler or insert 5 is completely encased except 60 for the top portion thereof on which there is no wear, and aluminum being a hard metal will resist strains to which the club head is subjected.

Various changes in the form, shape, proportion and other minor details of construction may be made without departing from the principle or sacrificing any of the advantages of the claimed invention.

I claim:

1. A golf club head comprising a thin metal casing having an insert of wood or the like conforming to the shape thereof and encased therein except at the top thereof, thus combining lightness with durability.

2. A golf club head comprising a thin aluminum casing having a rearwardly and upwardly projecting tubular extension and having one side thereof flattened and 80 equipped with a removable plate, a wooden filler mounted in said casing and conforming to the shape thereof, and screws entering through the bottom of the casing and through said plate and engaging the filler, 85 said filler being encased entirely in metal except at the top thereof thus combining lightness with durability.

In testimony that I claim the foregoing as my own I have hereto affixed my signature.

ELZIE HARNESS.
